Patented Dec. 11, 1923.

Des. 63,480

UNITED STATES PATENT OFFICE.

RALPH H. NESMITH, OF DETROIT, MICHIGAN, ASSIGNOR TO MORGAN & WRIGHT, OF DETROIT, MICHIGAN, A CORPORATION OF MICHIGAN.

DESIGN FOR A TIRE.

Application filed June 30, 1923. Serial No. 6,632. Term of patent 14 years.

To all whom it may concern:

Be it known that I, RALPH H. NESMITH, a citizen of the United States, residing at Detroit, county of Wayne, and State of Michigan, have invented a new, original, and ornamental Design for Tires, of which the following is a specification, reference being had to the accompanying drawing, forming part thereof, wherein the figure is

a perspective view of a section of a tire showing my new design.

I claim:

The ornamental design for a tire as shown. Signed at Detroit, in the county of Wayne, and State of Michigan, this 27th day of June, 1923.

RALPH H. NESMITH.
